CLAIM

The ornamental design for a bottle, as shown and described.

DESCRIPTION

The patent or application file contains at least one drawing executed in color. Copies of this patent or patent application publication with color drawings will be provided by the Office upon request and payment of the necessary fee.

FIG. 1 is a top plan view of a bottle showing my design according to one aspect;

FIG. 2 is a front side elevation view of FIG. 1;

FIG. 3 is a bottom plan view of FIG. 1;

FIG. 4 is a right side elevation of FIG. 1;

FIG. 5 is a left side elevation of FIG. 1;

FIG. 6 is a rear side elevation of FIG. 1;

FIG. 7 is a top plan view of a bottle showing my design according to another aspect;

FIG. 8 is a front side elevation view of FIG. 7;

FIG. 9 is a bottom plan view of FIG. 7;

FIG. 10 is a right side elevation of FIG. 7;

FIG. 11 is a left side elevation of FIG. 7;

FIG. 12 is a rear side elevation of FIG. 7;

FIG. 13 is a top plan view of a bottle showing my design according to yet another aspect;

FIG. 14 is a front side elevation view of FIG. 13;

FIG. 15 is a bottom plan view of FIG. 13;

FIG. 16 is a right side elevation of FIG. 13;

FIG. 17 is a left side elevation of FIG. 13;

FIG. 18 is a rear side elevation of FIG. 13;

FIG. 19 is a top plan view of bottle showing my design according to still another aspect;

(Continued)

FIG. 20 is a front side elevation view of FIG. 19;
 FIG. 21 is a bottom plan view of FIG. 19;
 FIG. 22 is a right side elevation of FIG. 19;
 FIG. 23 is a left side elevation of FIG. 19;
 FIG. 24 is a rear side elevation of FIG. 19;
 FIG. 25 is a top plan view of bottle showing my design according to still yet another aspect;
 FIG. 26 is a front side elevation view of FIG. 25;
 FIG. 27 is a bottom plan view of FIG. 25;
 FIG. 28 is a right side elevation of FIG. 25;
 FIG. 29 is a left side elevation of FIG. 25;
 FIG. 30 is a rear side elevation of FIG. 25;
 FIG. 31 is a top plan view of bottle showing my design according to a further aspect;
 FIG. 32 is a front side elevation view of FIG. 31;
 FIG. 33 is a bottom plan view of FIG. 31;
 FIG. 34 is a right side elevation of FIG. 31;
 FIG. 35 is a left side elevation of FIG. 31; and,
 FIG. 36 is a rear side elevation of FIG. 31.

The light blue and white color shown in FIGS. 1-6, the yellow and white color showing in FIGS. 7-12, the purple and white color shown in FIGS. 13-18, the light green and white color shown in FIGS. 19-24, the pink and white colors shown in FIGS. 25-30 and the blue and white colors shown in FIGS. 31-36, form a part of the claimed design. The trademark “WONDERLAB” forming part of the claimed design is a trademark owned by Shenzhen Meili Nutrition Technology Co., Ltd. (U.S. Trademark application Ser. No. 90/577,038).
